FLUID PRESSURE INSTRUMENT

Wilfred Owen Davis, London, England, assignor
to S. Smith & Sons (Motor Accessories) Limited,
Cricklewood, London, England, a British
company

Application April 30, 1941, Serial No. 391,203
In Great Britain February 16, 1940

2 Claims. (Cl. 73—4)

This invention relates to fluid pressure operated instruments of the kind in which the movements of a fluid pressure operated flexible diaphragm are transmitted to an operating mechanism including an indicating or control member, for example, a pointer moving over a scale, and in which a limiting stop is provided and is engaged by a part of the operating mechanism to prevent excessive movement of the indicating or control member. If, however, the movement of the diaphragm is suddenly arrested by the limiting stop, the mechanism is liable to be damaged and the object of the present invention is to overcome this difficulty.

According to the present invention, there is provided a fluid pressure operated instrument of the kind specified, wherein the operating mechanism comprises a lost motion connection between the diaphragm and that part of the mechanism which engages the limiting stop and a spring or other resilient means biasing the said part of the operating mechanism towards the limiting stop. When this arrangement with the limiting stop is engaged, the diaphragm is not suddenly arrested but is permitted to move with lost motion.

According to a further feature of the invention the resilient biasing means is connected between said part of the operating mechanism and a fixed abutment, so that when the limiting stop is engaged, the diaphragm can move freely through the extent of the lost motion.

In a preferred construction the lost motion connection is provided between the diaphragm and a link connecting the diaphragm to a crank on a rockshaft of the operating mechanism, the movement of which shaft is restricted by the limiting stop and wherein the resilient biasing means consists of a spring connected at one end to the rockshaft and at the other end to the fixed abutment.

One application of the invention to a barometric altimeter is illustrated by way of example in the accompanying drawing, in which—

Figure 1 is a cross-section of the instrument, and

Figures 2 and 3 are enlarged detailed views at right-angles to one another.

Referring to the drawing, the altimeter comprises coupled barometric capsules 10, carried at one side on a pillar 11, fixed to a frame 12 to the instrument. At the other side of the capsules there is a post 13 having a lengthwise slot 16 receiving one end of a link 15. This link has a lengthwise slot 16, receiving a cross pin 17 fixed in the post 13. The other end of the link 15 is connected by a pivot 18 to a crank

19 fixed to a rockshaft 20, which is rotatably mounted in the frame 12. This rockshaft is connected by a linkage or gearing to one or more pointers in the usual manner. The movements of the rockshaft as a result of expansion of the capsules is limited by a stop 21 on the frame 12 and engaged by the crank 19. A coiled spring 22 is connected to one end of the rockshaft 20 and at the other end to a post 23 on the frame 12. The spring 22 is arranged rotationally to bias the shaft 20 to urge the crank 19 towards the limiting stop 21, thus holding the link 15 with the outer end of the slot 16 in engagement with the pin 17, as shown in Figure 2. The movements of the post 13, as a result of expansion of the capsules thus allows the rockshaft to be turned by the spring 22. The movements of the post 13 as a result of construction of the capsules turns the shaft 20 against the action of the spring 22. If excessive expansion of the capsules occurs to bring the rockshaft to its limiting position, the capsules can continue to expand by reason of the pin 17 being permitted to travel along the slot 16 without any load to be provided on the mechanism. The mechanism is thus protected from damage which might result from such excessive expansion.

I claim:

1. A fluid pressure operated instrument comprising a flexible diaphragm, a diaphragm operated member, a transmission mechanism affording a positive driving connection from the flexible diaphragm to the said operated member, a limiting stop engaged by a part of said mechanism to restrict the motion thereof, said mechanism having a lost motion connection between said diaphragm and said part, resilient means biasing said part towards the said limiting stop and a fixed abutment for the resilient means, said resilient means being connected between said part and said fixed abutment.

2. A fluid pressure operated instrument comprising a flexible diaphragm, a diaphragm operated member, a transmission mechanism affording a positive driving connection from the flexible diaphragm to the said operated member, said transmission mechanism comprising a rockshaft, a crank on said rockshaft and a link connecting said diaphragm to said crank, said link having a lost motion connection with said diaphragm, a limiting stop restricting the extent of rotation of said rockshaft, a fixed abutment, and resilient means connected between said fixed abutment and the rockshaft and biasing said rockshaft towards the position in which it is halted by said limiting stop.

WILFRED OWEN DAVIS.
